UNITED STATES PATENT OFFICE.

FRITZ NATHO, OF OPPENHEIM, GERMANY.

SWIMMING GLOVE.

Application filed May 10, 1927, Serial No. 190,319, and in Germany March 1, 1927.

This invention relates to a glove designed to be used at swimming to facilitate the exertion of this sport.

According to the invention a piece of fabric is fixed on the inner surface of a glove, said piece of fabric corresponding in size to the size of the inner surface of the hand when the fingers are spread, said piece of fabric having at the portions between the 10 finger points a bead with outer edge and a longitudinal groove at the middle.

An embodiment of the invention is shown, by way of example, in the accompanying drawings in which:—

Fig. 1 shows in plan view a glove with spread fingers viewed on the hand back.

Fig. 2 is a cross section on line II—II of Fig. 1.

To the inner side of the glove *a* a piece *b* of fabric, leather or rubber is fixed, which corresponds in size to the inner surface of the hand when the fingers are spread. This piece *b* is either sewn onto the glove or stuck on the same. Webs *d* extend along the 20 front edge of said piece *b* at the portions situated between the fingers of the hand. In each portion of piece *b* between two fingers a longitudinal groove *e* extending along the middle line of said portion is 25 provided which forms a rib projecting on the inner surface of the hand. The front edge of the portions of piece *b* between the fingers is beaded. The glove has webs like paws of swimming birds, geese, ducks and 30 the like.

The fabric for the web must be resistant but sufficiently soft to fold together on the inner surface of the hand when the fingers are not spread.

The webs must not be fixed between the fingers as otherwise the fingers cannot be brought into contact the one with the other and as the web must fold up on the inner surface of the hand when the fingers of the hand are not spread out. The advantage of the swimming gloves is evident. A hand which tends to grip something spreads automatically the fingers and this would be the 40 45

case at the swimming, when the water had sufficient body. As this is however not the 50 case, the fingers of the hand must be closely held together to oppose a greater resistance to the water. When a person wears swimming gloves the fingers of the hand are spread automatically as soon as the hand is 55 pressed against the water, the pressing surface being considerably enlarged by the stretched web without any special effort.

The swimming movements can be carried out by the swimmer with much greater ease 60 than without the gloves and the energy exerted gives almost double the result as without the swimming gloves.

When swimming the hands are pushed forward as usual lying the one against the other the webs of the two gloves being folded up on the inner surfaces so that they cannot oppose any resistance to the water. When swimming the swimming gloves present an enormous advantage and facilitate the swimming. The webs prevent cramp in the fingers as, when the hand is being stretched against the water the fingers are spread out, the web is stretched and the position of the fingers is regulated without any exertion. 70 75

As soon as the back of the hand is moved through the water the fingers close and the webs are folded on the inner surface of the hand and do not oppose any resistance to the water. 80

I claim:—

A swimming glove comprising in combination with the glove proper, a piece of suitable material as fabric, leather, rubber, fixed on the inner surface of the glove and corresponding in size to the size of the inner surface of the glove with spread fingers, the edge of the portions of said fabric between the fingers and which form each a web between two fingers being beaded and a groove pressed into each portion between two fingers along the middle line of the same forms a corresponding rib on the inner surface of the corresponding portion. 85 90 95

In testimony whereof I affix my signature.
FRITZ NATHO,
